UNITED STATES PATENT OFFICE

AUGUSTINE H. MASSEY, OF STRATFORD, CONNECTICUT, ASSIGNOR TO COLUMBIA PHONOGRAPH COMPANY, INC., OF BRIDGEPORT, CONNECTICUT, A CORPORATION OF NEW YORK

DESIGN FOR A CUBE TAP

Application filed July 21, 1932. Serial No. 44,392. Term of patent 7 years.

To all whom it may concern:

Be it known that I, AUGUSTINE H. MASSEY, a citizen of the United States, residing in Stratford, in the county of Fairfield and State of Connecticut, have invented a new, original, and ornamental Design for a Cube Tap, of which the following is a specification, reference being had to the accompanying drawing, forming a part thereof.

I claim:

The ornamental design for a cube tap, substantially as shown.

AUGUSTINE H. MASSEY.
